UNITED STATES PATENT OFFICE.

AUGUST CONRAD DEWIES, OF CREFELD, PRUSSIA.

IMPROVEMENT IN LUBRICATORS.

Specification forming part of Letters Patent No. 36,703, dated October 21, 1862.

To all whom it may concern:

Be it known that I, AUGUST CONRAD DEWIES, of Crefeld, in the Kingdom of Prussia, have invented a certain new and useful Improvement in Lubricators, of which the following is a full, clear, and exact description, reference being had to the accompanying drawings, which make part of this specification, and in which—

Figure 1 represents a vertical longitudinal section through my improved apparatus at the line *x x* of Fig. 2; and Fig. 2 a vertical transverse section through the same at the line *y y*, Fig. 1.

The lubricating devices heretofore employed require the use of so much oil that it flows through the oiling-hole as well during the repose of the axle as when it is in motion. This waste, besides being quite useless and unnecessary, makes the machinery near the oil-cups very dirty and greasy. Plates or dripping-pans are sometimes placed under the axle-boxes to catch the drippings; but this cannot be done perfectly without a great deal of trouble and expense. Again, in many manufactories the axle-boxes are mostly either in dark rooms or at a considerable height from the ground. As it is difficult to inspect such boxes even with the aid of a stair or ladder and a light, the journals are often allowed to become heated before their want of lubrication is discovered.

It is the object of my invention to avoid the above-mentioned and other defects incident to lubricators constructed as hereinbefore described, and to provide a simple, cheap, and efficient lubricating apparatus, to which end my improvement consists in the employment of a glass vessel into which a tube or cylinder is inserted, the mouth of the vessel being closed with a cock through which the tube passes. The end of the tube which is inserted into the vessel is closed, with the exception of a minute orifice. A similar orifice, through which the oil escapes, is also made in one side of the tube. The lower or outer end of the tube is open and fits closely upon the axle to be lubricated, so that when in repose no oil escapes; but when the axle rotates the oil is drawn down and lubricates the journal, the vacuum thus caused in the vessel being filled by the air which percolates through the cork.

In the accompanying drawings my improved

apparatus is shown as consisting of a bottle, A, the mouth of which is fitted with a cork, C, through which a tube, B, passes. The upper end of this tube is closed, with the exception of a minute opening, through which the oil flows. A similar aperture is also made in the side of the tube. The outer end of the tube is open and fits accurately upon the shaft E.

The operation of the lubricator is as follows: The bottle A is filled with oil and the cork C and tube B inserted into it. The bottle is then turned upside down and the tube B inserted into a hole in the axle-box D in such manner that its mouth fits closely upon the shaft E. As the shaft revolves the oil is drawn down by the suction thus produced, and lubricates it; but when the axle ceases to rotate the flow of oil is also stopped, the vacuum created by the flow of oil being filled by air which percolates through the cork.

The advantages attained by the use of my improved apparatus are perhaps greater than would strike a casual observer. Owing to the transparency of the oil-cup, a glance serves to show the quantity of lubricating material it contains, no matter where situated. The construction of the lubricator, moreover, is so simple that it can be made or repaired by any person of even the most ordinary ability.

The saving of oil by the use of my invention is very great, amounting, as I have demonstrated by experiment, to at least one-half the quantity consumed by the lubricators heretofore generally used.

Having thus fully described the construction and operation of my improved lubricator, what I claim therein as new, and desire to secure by Letters Patent, is—

The combination of the transparent vessel A, the stopper C, and the tube B, having its flow regulated by the perforations in the end within the vessel A, and the other end adjusted to the curvature of the shaft, with the journal-box D and shaft E, when the whole are constructed, arranged, and operated as described, for the purpose set forth.

In testimony whereof I have hereunto subscribed my name.

AUGUST CONRAD DEWIES.

Witnesses:

G. JOSEPH RUCH,
P. L. FEIRTY.
